The Lowell Manufacturing Company of the said place
Letters Patent No. 3022 Dated Jan'y 17 1865.

Design for a Carpet Pattern.

The schedule referred to in these Letters Patent and making part of this same.

To all whom it may concern:

Be it known that I, Eleazar Kelley of Lowell
in the County of Middlesex and State of Massachusetts have arranged
and designed a new pattern for carpets or other fabrics of which
the following is a full, clear and exact description, reference being
had to the accompanying drawings, making part of this specification.

A is a small set figure composed of omitted work resting
on ground. B and C surrounded by a border consisting of small
balls.

1, 2, and 3 in the corners of the design are fourths of a
centre similar to A, B and C.

D is a connected scroll resting on coral and sprig work.

4, 4, 4, 4 are fourths of a connected scroll similar to D, like-
wise resting on coral and sprig work.

E, F, G and H are halves of a pointed set figure surround-
ed by the scalloped border 5, 5, 5, 5.

The remainder of the design is occupied by small leaves.

Note.

This specification refers to that part of the drawings be-
tween the blue lines.

The colors employed for the different portions of the
design may be varied to suit the taste and wish of the man-
ufacturer.
